THYRATRON TUBE

Howard B. Sloan, Swampscott, Mass., assignor to
Sylvania Electric Products Inc., Salem, Mass.,
a corporation of Massachusetts

Application March 29, 1945, Serial No. 585,491

5 Claims. (Cl. 250—27.5)

1

This invention relates to thyratrons, and particularly to hydrogen-filled thyratrons.

Objects of the invention are the production of short sharp pulses, the prevention of undesirable flash overs, and the prevention of clean up of the gas in the bulb.

These objects are obtained by the use of hydrogen as a gas filling, a beaded anode lead with a separate enclosing insulating tube, and the use of a cathode coated on its sides only, with its sides surrounded by a shield spaced reasonably closely thereto. The device is especially effective when the electron current carried by the tube is in excess of the normal thermionic emission of the cathode.

The invention will be described with reference to the accompanying drawings, in order to make clearer further objects, advantages and features of the invention.

Figure 1 shows a section perspective of a tube according to the invention;

Figure 2 shows a seal which is one embodiment of the invention; and

Figure 3 shows a longitudinal section through the center of the tube.

In the figures, the glass tube 1 has the lead-in wire 2 sealed through and closing one of its ends with the stem 3 through which additional lead-in wires 4, 5, and 6 extend, sealed to and closing the opposite end. The tungsten filament coil 7 is attached at one end to the conductor 8 which supports it from the lead-in wire 5 to which it is electrically connected. A coating of refractory insulating material such as aluminum oxide is used on the filament turns to prevent short-circuiting thereof on sagging. The other end of filament coil 7 is connected by the metal tabs 9 and 10 to the disc 11 whose flanged edges 12 are attached to nickel cylinder 13, which is coated on its outside diameter with an electron emitting mixture of barium and strontium oxides. This coating is best terminated a short distance from each end of the cylinder. The bottom of the cylinder is attached by the disc 14 through which the conductor 8 passes and from which it is spaced or insulated. A disc of larger diameter 15 is attached to the disc 14 and extends beyond the diameter of the cathode 13, to support the cathode shields 16 and 17 which may be attached to the flange or rim 18 at the outside of the disc. The two cathode shields are preferably spaced apart a short distance. The collar 19 supported from the top of shield 17 in turn supports the shielding discs 20, 21 and 22 which are spaced from each other and attached to the collar 19

2

by the conductors 23 and 24. The cathode shields 16 and 17 may be supported by the wires 25 and 26 extending from a collar 27 around the base of stem 3, to insure rigidity.

Anode 28 is a circular metal disc attached to and supported by the lead-in wire 2 over which the glass sheath 29 is sealed, extending from seal 30 to a point close enough to the anode 28 to prevent flash over. The glass tube 31 concentric with the sheath and spaced therefrom, extends along the entire length of the sheath and merges with the sheath into the seal 30 through which the lead-in wire 2 extends to be attached to the contact 32 by the solder 33. A collar 34 around the free end of glass tube 31 is attached to the transverse disc 35 which shields the top of the anode 28. The grid 36 of metal gauze is attached to the flange edge 37 of disc 35 at the top of anode 28 and to the collar 38 below anode 28. The perforated disc or grid 39 is affixed to the collar 38. The additional spider 40 connects the disc shield 41 to the grid 39 and spaces it therefrom. The construction of the spider 40 provides an electron path around the periphery of the disc shield 41. The anode 28 is thus completely surrounded by a structure comprising the grids 36 and 39 through which electrons from the cathode 13 must pass to reach said anode 28. The spacing between the anode 28 and the various parts of the grid should be small enough to prevent flash back between the parts. The shielding disc 41 serves to prevent any metal evaporated from the filament from depositing on the grid 39 and causing it to emit electrons. For the most part however, the material evaporated from the cathode 13 will be deposited on the shield 16 concentric with the cathode.

The bottom part of the grid 36 is attached to the metal cylinder 42 which helps to support it and also acts as additional heat shield for the cathode 13. Cylinder 42 is supported at its bottom by the wires 43 and 44 which are sealed into stem 3. The conducting ribbons 45 and 46 connect lead-in wires 43 and 44 with the cylinder 42 to insure good electrical contacts therewith. Tabs such as 47 may be used to assist in connecting lead-in wires 43 and 44 to the cylinder 42. Similar tabs 48 may be used to aid in connecting shield 17 to its support wires 25 and 26. The base 49 may be cemented to the bottom part of the tube 1 by the cement 50 and the lead-in wires 4, 5, and 6 may be connected to the contact prongs 51, 52, 53, 54 of the base which are insulated from each other. Prong 52 may be con-

nected inside the base to prong 51 by the jumper connection 55.

The tube is of course evacuated and filled with hydrogen at a pressure of 0.6 mm., for example.

In operation current is passed through the filament 7 which serves to heat the nickel cylinder 13 and the emitting coating upon it. The electrons emitted therefrom pass through the gas in the tube and eventually through the grids 36 and 39 to reach the anode 28. The grids 36 and 39 can thus be used to control the starting of the discharge as in the usual thyratrons and because of the use of hydrogen as the gas filling the discharge will deionize rapidly when the anode voltage is removed.

Prior to my invention the clean up of hydrogen in tubes of this sort was a serious problem. I find that in a tube of my novel construction however, the hydrogen is not cleaned up appreciably. This appears to be due to the fact that the electrons are all emitted from the outside of the cylinder 13 and passed through the confined space between the cylinder and the shield. Barium or strontium particles sputtered from the cathode will be picked up by the inside surface of the shield 16. The combination of these barium and strontium particles with the hydrogen to form a hydride may be the cause of the hydrogen clean up and in my particular construction the particles fall on the shield close to the cathode, apparently under such equilibrium conditions as cause the hydrogen to be removed therefrom. The absence of cathode coating from the top 12 of the cathode insures that all the sputtered particles will come from the sides of the cathode. In tubes prior to my invention the sputtered particles appear to have had a comparatively free path through the interior of the tube.

I find also that it is well to operate the tube at currents in excess of the normal thermionic electron emission of the cathode for the temperature at which it is operated. For example, the cylinder 13 may have a diameter of $1\frac{1}{8}$ inch and a height of $1\frac{1}{4}$ inches, with an uncoated space of 0.4 cm. at each end of the cylinder. This gives a coated area of about 14 cm^2 , for the barium and strontium oxide coating; and yet peak currents as high as 350 amperes may be safely carried by the tube without reducing its life below the present rating of 500 hours. Actually I have found a coating area extending from a point 0.4 cm. from the top of the cylinder 13 for a distance of 0.8 cm. downward to be sufficient for such a life.

The anode 28 and its surrounding grid structures 35-36-38 are spaced quite closely together, for example, 0.80 inch, and will not flash over with the gas pressure used, because of the well known short-path principle. However, were it not for the sheath 29, flash over could occur between the grid structure 35, 36, 39 and the more remote parts of the lead-in wire 2 inside the tube. The sheath prevents this flash over and should extend close enough to the anode 28 to insure a short enough path to the unsheathed portion of the lead-in tube to prevent flash over. The space tube 31 is an additional safeguard and also helps to support the disc 35. For example, my tube may use an anode voltage as high as 16,000 volts without flash over under these conditions. The distance from the anode 28 to the outer edge 56 of seal 30 should be quite long to prevent electrolysis at the seal. For the voltage used, I find a distance of about 7.2 cm.

to be sufficient. The distance inside the tube from the anode 28 to the inner edge 59 of the seal is more important, and should be about 5.3 cm. for the voltage used.

5 The tube may be made somewhat shorter by making the seal in a reentrant form as shown in Figure 2. In this case the tube 58 extends into the enclosing envelope and outward again as tube 31 to be sealed to the sheath 29 at point 59, which then extends upward out of the tube. The grid support collar 34 is then attached to the reentrant tube 58 as shown.

10 The oxides in the coating on cathode 13 may, of course, be applied as carbonates and converted to the oxides by heating during exhaust in the manner well-known to the art.

15 When not carrying current the voltage drop across the tube may be 16,000 volts, but when application of sufficient voltage to the grid 36 causes the tube to "fire" and pass current, the voltage across the tube may be as low as 100 volts or less for a current of 300 amperes, the remaining voltage appearing in the load circuit. The grid voltage for "firing" the tube may be 20 about 150 volts in some cases, although it is generally applied in such transient form as to make its measurement difficult.

25 The voltages and current here given are for the peak value of the pulse through the tube, as far as they can be ascertained. The average current through the tube may be less than an ampere.

30 What I claim is:

1. A thyratron comprising an enclosing glass envelope having a first tubular reentrant portion and a second tubular portion reentrant into said first reentrant portion, a lead-in wire sealed through the end of said second tubular portion and extending into said envelope for a considerable distance concentric with and spaced radially from said second tubular portion, a glass sheath extending along said wire and inside but spaced radially from said second tubular portion for substantially its entire length, an anode in said envelope and supported by, and transverse to said lead-in wire, a grid inside the envelope and surrounding said anode and supported from said first tubular reentrant portion by a collar thereon and a cathode in said envelope.

35 2. An electrode support comprising an enclosing glass envelope, a reentrant tubular structure including an outer glass tube joined to and extending into said envelope and a second glass tube coaxially within said outer tube and joined thereto at its inner end, a lead-in wire coaxially within said second tube and sealed thereto at the outer end of said second tube, and a glass sheath extending along and in contact with said wire for the greater part of the length thereof.

40 3. A thyratron comprising a glass envelope, a lead-in wire sealed therethrough and extending into said envelope a substantial distance and supporting an electrode, a glass sheath sealed to said lead-in wire along most of its length, a glass tubular structure concentric with said sheath and extending therewith from said envelope, and another electrode secured to said glass tubular structure at the innermost end thereof.

45 4. A thyratron comprising an enclosing glass envelope having a reentrant tubular structure including an outer glass tube and a second glass tube coaxially within said outer tube, said tubes being joined together at their innermost ends, 50 a lead-in wire coaxially within said second tube

55 75 a lead-in wire coaxially within said second tube

and sealed thereto at the outermost end of said second tube, a glass sheath extending along said lead-in wire for most of its length inward from the point of sealing to said second tube, an electrode joined to the innermost end of said lead-in wire, and a second electrode mechanically connected to and supported by the innermost end of said reentrant tubular structure.

5. A thyratron comprising an enclosing envelope, an anode transverse to the longitudinal axis of said envelope, a grid substantially surrounding said anode, an insulating tube sealed to said envelope and extending thereto, a lead-in wire sealed to said tube and extending into said envelope coaxially within said tube, an insulating sheath sealed around said lead-in wire for substantially the entire length of said tube, a mechanical connection between said grid and said tube providing support for said grid, a cylindrical cathode with closed ends separated from said anode by said grid, a coating of alkaline earth oxides on only the cylindrical sides of said cathode and terminating a short distance from the ends of the cylindrical sides thereof, said ends being free from said oxides, a metal shield concentric with said cathode and spaced closely

therearound and connected thereto, and a second metal shield concentric with said cathode and outside and around said first shield and connected to said grid, the cathode and both metal shields being concentric with the longitudinal axis of the cylinder, said envelope having a filling of hydrogen.
